(57) **CLAIM**

The ornamental design for a fruit dehydrator, as shown and described.

DESCRIPTION

FIG. 1 is a left front perspective view of a fruit dehydrator showing my new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.

The structural features depicted by broken lines in FIGS. 1, 2, 3, 4 and 7 have been shown for the purpose of illustrating portions of the fruit dehydrator that form no part of the claimed design.
